UNITED STATES PATENT OFFICE

DANIEL H. DORSETT, OF CHICAGO, ILLINOIS.

UNDERGROUND CONDUCTOR.

SPECIFICATION forming part of Letters Patent No. 340,431, dated April 20, 1886.

Application filed October 15, 1885. Serial No. 179,961. (No model.) Patented in England October 30, 1885, No. 13,169.

To all whom it may concern:

Be it known that I, DANIEL H. DORSETT, a citizen of the United States, residing at Chicago, in the county of Cook and State of Illinois, have invented certain new and useful Improvements in Underground Conductors, of which the following is a specification, reference being had to the drawings accompanying and forming a part of the same.

10 My invention is an improvement in systems of underground electric conductors, the improvement being directed to facilitating the laying and distribution of the conductors throughout a city or any part of the same; to 15 the better insulation of said conductors, and the prevention of inductive or other injurious effects arising from the close proximity of circuits for different purposes, such as telegraphing or telephoning on the one hand and 20 electric lighting on the other.

My system is comprehensive and complete in so far as it provides for the economical laying and working of all the circuits which the present needs of business and communication 25 require. In other words, I provide for the running in close proximity of circuits for carrying the strongest and most intense currents, as well as those for carrying the most feeble electrical impulses—such as are produced in the operations of telephony—and this in such manner there will be no danger to any circuit from such proximity, while all are brought within ready and easy access. The system comprises main and branch pipes or 30 conduits, in which the conductors are carried in the manner hereinafter specified. The mains consist of three separate and independent pipe-lines, one containing such wires as are required for communication with distant 35 points or other cities, and which will be hereinafter designated as "trunk-lines." Another pipe contains the wires of circuits used in local communication and intercommunications—such as telephone-lines, fire and burglar 40 alarm circuits, and the like—while the third contains the circuits used for electric lighting, transmission of power, or those industrial and domestic applications of electricity which require powerful currents. The lines are run 45 through the streets of a city at such a distance below the surface as will insure protection 50 against bending or injuries from repair of the

streets, subsidence of the surface soil, and the like. Generally and whenever convenient the lines are run midway between the buildings on either side of the way, and with the trunk-line between the other two. At the intersections of the streets the three lines are run into what I term "man-holes"—that is, subterranean chambers—large enough to permit a man 55 to enter them for obtaining access to the pipes or conductors therein. These man-holes are constructed in a way to keep out water and other matter, and are provided with suitable detachable covers. The pipes pass through 60 their sides, and the wires are carried from one pipe to another, as may be required. Between the man-holes and along the blocks or squares are numerous subterranean chambers, which I designate "hand-holes." These are 65 placed as nearly as practicable opposite the dividing-lines between the buildings, so that in places where the buildings are of about the same frontage two hand-holes are required for each group of four houses, as will shortly be 70 explained.

The hand-holes are for the purpose of running branches from the two pipe-lines on either side of the trunk-line, which latter does not pass through them. They are much smaller than the man-holes, though constructed on the same principle. The pipes containing the signaling and those with the electric-light wires enter these boxes, and one or more of the wires or branches from the same are brought 80 up to a higher level and taken off into smaller branch pipes to the buildings. Four of the smaller pipes run from each hand-hole, one to each of the four nearest buildings, and in laying the hand-holes and branches it is desirable 85 to locate the former as near as possible to each other, in order that all the branches may be placed in laying in one small trench. Of the two branch pipes that run to each house, therefore, one contains the wires of an electric-light 90 circuit, the other those of a telephone or other signaling circuit. In the case of the former there may be one or more leading and return wires for the same house-circuit, or the leading wire or wires to one house and the return 95 wire or wires from another. This is obviously a matter of choice and not essential to the main features—that of isolating the electric-light circuit from the others.

In a former patent, No. 305,904, I have described an underground conduit for electrical conductors made of an insulating compound containing coal-tar, paraffine, silicious sand, 5 pulverized ashes and cinders, oxide of manganese, and ammonium chloride, in about the proportions hereinafter specified. This material I use for the mains of my system, preferring it to all others. The joints between the sections of the pipes may be either of metal, as set forth in the said patent, or the entire conduit may be made from the insulating material alone. I make the man-holes of this material also, their construction being fully described 10 in a patent granted to me July 21, 1885, No. 322,529, except that in the present instance I make them oblong or oval in cross-section. The hand-holes are also made of this material, their specific construction being hereinafter 15 more fully described.

Inasmuch as the mains are buried deep and are of comparatively large size, they are advantageously made of the insulating compound alone; but it is extremely undesirable to bury 20 the branch pipes deep. In fact they should be but little below the surface or flagging of the street, and as they carry usually only one or two wires they should be made quite small.

Instead of making them therefore of the compound alone, I use iron pipes, which I fill with the compound, through which passages are formed for the wires. By this means the 25 requisite strength and insulation are obtained.

With this general description of the nature 30 of the system, I will now describe the specific construction and composition of the parts of the same by referring to the drawings annexed hereto.

Figure 1 is a general plan or diagram of a 35 portion of the system as applied to a city or town. Fig. 2 is a vertical central section of one of the man-holes. Fig. 3 is a plan view of the same. Fig. 4 is a plan view of a part of the line, exhibiting the arrangement of the 40 hand-holes. Fig. 5 is a broken section of Fig. 4, taken through the centers of the hand-holes.

Similar letters of reference indicate corresponding parts in the several figures.

In Fig. 1 is illustrated a portion of a city at 45 the intersection of two streets. The underground lines are laid at or near the middle of the street, and are inclosed in the pipes. That indicated in continuous lines is the trunk-line, and is lettered A.

The conduit B, in dotted lines, contains the 50 local signaling-circuits, while C, in broken lines, contains the electric-light and power-circuits.

The three lines or systems are laid in the 55 same trench on the same or different levels, and preferably with the trunk-line in the center. At the intersection of the streets the three pipes enter man-hole D. The details of the construction of this are shown in Figs. 2 and 60 3. It is a large box or chamber made of molded slabs or in one piece of the insulating compound described by me in former patents,

and consisting of residuum of partially-distilled coal-tar, paraffine, silicious sand, pulverized ashes and cinders, oxide of manganese, 70 and ammonium chloride in about the proportion of fifty gallons of coal-tar, two of paraffine, one hundred and fifty pounds of silicious sand, fifty of ashes and cinders, two pounds of oxide of manganese, and one of ammonium 75 chloride. These ingredients, when thoroughly mixed and heated, form a plastic compound, which is molded in the desired shape, and which when cool becomes extremely hard.

The man-holes have a contracted opening 80 at the top, which is closed by the following means: A metal rim, E, is placed in the mold or on the material while soft. On hardening, the compound adheres to the rim; but it may be secured by other means, if deemed expedient. A cross-bar, F, is properly secured in the rim, and the cover is held down by a screw-bolt, G, that passes through the cross-bar.

I prefer to make the man-hole oval or oblong in cross-section, as shown in Fig. 3, and 90 to introduce the mains through its broader sides. The mains are made of the same material as the man-hole, and they are joined to it by passing their ends through holes in its sides and ramming in some of the same material while soft around their ends. In each man-hole is a partition, H, or several, if desirable, that extend up above the level of the mains, dividing the space within the man-hole into compartments. In one of these compartments the electric-light wires enter, so that they are entirely shut off from the other circuits by a wall of insulating material. The mains enter and leave the man-holes on opposite sides; but where it is necessary to run 100 either trunk-lines or local circuits off on side streets other conduits, K L, are joined to the man-holes, as shown in Fig. 2.

The man-holes permit easy access to all the 110 circuits. The entering wires are here distributed to the proper conduits, repairs or tests made, or new circuits introduced. The mains are for this purpose made with a certain number of ducts or passages, a, Fig. 2, through which the wires are drawn.

For running the circuits to the different 115 houses, I use the junction-boxes or hand-holes shown in Figs. 4 and 5. These are connected with the electric-light and local-wire conduits only, and are placed as near together as practicable, in order that the pipes running from them may be laid in the same trench. These hand-holes are made of the same material as the conduits and man-holes, are similar to them in many respects, and are provided with 120 the same or similar covers. They are much smaller and shallower, however, extending down only slightly below the level of the mains. The latter are joined to them in the same manner as to the man-holes.

In the diagram Fig. 1 I have represented 130 the houses and buildings along the street. The division-lines between the buildings are designated by M, and as near as practica-

ble in line with these two hand-holes are placed. Tubes run direct from the hand-holes to the buildings. From the hand-holes N on the electric-light conduits run the branch pipes 5 $m\ n$ and $m'\ n'$, and from the hand-holes O on the local signaling-conduit run branches $o\ p\ o'\ p'$. There will be four branch pipes from each hand-hole, and they enter them considerably above the level of the mains and 10 just below the service of the street. Such wires as are necessary are taken up from the mains and carried through these branches. It is desirable that these branches should be small, and that they should be near the surface, but I have found it desirable under these 15 circumstances to make them of stronger materials than are used in the mains. For this reason I use iron pipes or tubes provided with suitable couplings and filled with the material 20 composing the mains, through which ducts or passages are formed for the wires. My method of making them is to place an iron pipe of the desired length over one or more smaller rods or tubes fixed rigidly at one or both ends. 25 I then fill in the intervening spaces with the hot and soft insulating material, tamping it down to form a solid mass. I then withdraw the rods or tubes and allow the compound to harden. These pipes are joined to the hand-holes in the same manner that the insulating 30 mains are united to the man or hand holes. As the hand-holes are only designed to afford access to the wires in one pipe, they are much smaller than the man-holes.

35 I have thus described the complete system of underground distribution and protection of electric circuits which forms my invention. Of course, in practice the system may or may not be carried out in all its described details. 40 For instance, it is not requisite that branches be carried to every house on a block, as all the buildings may not need or use them; nor is my invention limited to a single pipe for the trunk-line or either of the others, as the 45 necessities of particular cases may require two or even more of one or all the kinds of pipe named. Further, so far as the general plan of distribution is concerned it is largely immaterial how or of what materials the conduits 50 and their appurtenances are made.

The particular advantages which I gain from this method of running underground lines are these: The conductors of different classes of circuits are entirely isolated from each other, so that injurious electrical inductive dis-

turbances are reduced to a minimum and the greatest safety assured. At the same time all the lines are brought into positions of easy access at the man-holes, one of the latter only being required for the three lines. 60

I do not claim herein any of the elements or parts of this system as independent instrumentalities, but only in the combinations in which they have here been described as entering and which effect the new and useful results set forth. 65

In other applications of even date herewith I have claimed both the specific construction of the man-holes and of the branch pipes. 70

What I now claim is—

1. In an underground system, the combination, with deeply-buried main conduits composed entirely of a plastic insulating material, of branch conduits from the same to the buildings along the way buried nearer the surface of 75 the street or roadway and made of iron pipes filled with an insulating material, as set forth.

2. In an underground system, the combination, with deeply-buried conduits composed entirely of a plastic insulating material, of 80 man-holes placed at the intersections of the streets and molded from the same or similar material, insulating hand-holes or junction-boxes placed at intervals along the conduits and branch pipes from the same buried nearer 85 the surface than the mains and made of iron pipes filled with an insulating material, as set forth.

3. In an underground system, the combination, with three deeply-buried and parallel 90 conduits containing, respectively, trunk, local-signaling, and electric-light lines and composed entirely of insulating material, man-holes placed at the intersections of the streets and to which all the conduits are led, hand-holes placed at intervals along the conduits containing the local-signaling and electric-light lines, the man-holes and hand-holes being composed of insulating material, and branch conduits from the hand-holes to the 95 buildings buried above the main conduits and near the surface of the street or road and composed of iron pipes with a filling of insulating material provided with ducts or passages for the wires, as set forth. 100

DANIEL H. DORSETT.
